UNITED STATES PATENT OFFICE

WILLIAM R. WATT, OF WILMINGTON, DELAWARE

AEROPLANE HANGAR

Application filed April 9, 1929. Serial No. 353,740.

The object of this invention is to provide a suitable storage space or hangar for heavier-than-air craft. In the type of hangar used at the present time, there is a considerable amount of waste space when individual stalls are used due principally to the peculiar shape of modern aeroplanes. When aeroplanes are stored in large hangars, it is extremely difficult to dispose them so as to economize in space. When it is desired to remove a plane from this type of hangar, it is often necessary to move all of the stored units to finally reach the particular plane desired. It is also obvious that, with a large hangar, in the winter time, there is a great heat loss due to the fact that the doors, which in most cases constitute one side of the building, must be opened, thereby exposing the interior to the outside air. It is also a fact that in case of a fire, in such a hangar, the possibility of localizing the flames is remote and there is little hope of saving all of the planes stored therein.

There has long been a demand on the part of aircraft operators and pilots for a type of hangar, which will provide at a reasonable cost, individual stalls each adapted to contain an aeroplane in such position that it could be readily removed and, at the same time, afford the advantage of permitting work on the plane without difficulty or cramping. In recognition of this need for a new type of hangar, the applicant sets forth in the following views a novel and improved de-

sign, of which

Fig. 1 is a sectional plan view taken on the line 1—1, Fig. 2, diagrammatically illustrating a preferred type of hangar;

Fig. 2 is a sectional view taken along the line 2—2, Fig. 1, showing in some detail the arrangement of the doors, windows and roof of the hangar; and

Fig. 3 is a diagrammatic view illustrating a modified arrangement of the stalls in the hangar.

Referring to Fig. 1, it will be noted that the individual stalls are represented by 1. The hangar is octagonal in shape, each stall 1 having a floor plan substantially in the form of an isosceles trapezoid. At the oppo-

site sides of the hangar are passageways 4 leading to a central space 5 for repair material, shops, offices, etc. The stalls 1, as shown in the preferred arrangement, consist of the side walls 6, a front entrance 7 having suitable doors 8, which are preferably of the folding type, opening to the flying field, and a back entrance 9 closed by the doors 10 and opening to the central repair and office space 5. An aeroplane 11 is shown diagrammatically in one of the stalls with both the front and rear doors closed and the aeroplane 12 is shown either leaving or entering one of the stalls. 13 represents a fuselage of a plane being taken from one of the stalls 65 into the space 5 where any extensive repairs that may be desired may be performed.

Fig. 2 shows particularly some of the details of construction. It may be noted that in order to secure ample light in the stalls 70 when the doors are closed, a shouldered roof 14 surmounts the stalls. This roof allows the windows 15 to be placed as shown in the break in the roof, giving light and, when necessary, ventilation for the individual stalls. 75 As mentioned heretofore, the doors 8, which are preferably of the folding type, open to the flying field. The doors 10 open into the central space 5 and the motor, wings, fuselage or any other part of the plane may be taken 80 through this back entrance 9 into the space 5 for repairs. The central space 5 is suitably ventilated and illuminated by the windows 16 which are placed in the walls 17 projecting above the tops of the stalls, and supporting the central part 18 of the roof 14.

It is obvious, therefore, that this particular arrangement makes a very desirable hangar structure.

As shown in Fig. 3, the arrangement of the stalls may be modified so as to dispense with the central space 5. In this plan, the stalls are built in a straight line side by side, alternately facing front and back. A plane landing on the particular field where this hangar 90 is located would taxi up to it and the pilot would be informed as to the particular stall which his plane is to occupy. He would then move his ship to a convenient position in front of this stall with the tail of the plane pointed 95 100

toward the entrance in a position similar to that of plane 12. The plane could now very easily be backed into the stall and housed for a time, or repaired as required.

- 5 In the hangar as shown in Figure 1, for instance, if it were necessary to weld a section of the fuselage, the wings could be detached and the fuselage removed from the stall through the rear doorway into the repair space 5, where everything could be done. In 10 inclement weather, all of the operations necessary could thus be performed inside. In its preferred form, the hangar is constructed entirely of fire-resistant material including 15 the doors 8 and 10. It, therefore, may be seen that in case of fire in any particular stall or in the center of the repair section, the fire-resistant construction of the entire structure, including the doors, would effectively prevent 20 the spreading of the flames.

The roof 14 slopes downward somewhat to the shoulder having the windows 15, and the walls 17 with the windows 16 are in substantial alignment with the rear backs of the 25 stalls 1. Between the windows 15 and 16 is a circular depression 19. The center 18 of the roof may be slightly arched. Suitable means may of course be provided to drain the section 19.

30 I claim:

1. A hangar having a plurality of radiating stalls, each with a floor plan of substantially trapezoidal form, a front entrance opening to the exterior of the hangar and a 35 back entrance opening into a space at the center of the hangar, two side walls set at an angle to conform to the general outline of an aeroplane, and a roof for the hangar the central space being of a size to receive the 40 fuselage of the aeroplane, the rear entrances permitting removal of the fuselage of an aeroplane disposed in any of said stalls to said central space.

2. An aeroplane hangar having a stall 45 with a floor plan of substantially trapezoidal form, a long front and a short back wall, two side walls diagonally arranged relative to said front and back walls, a roof downwardly offset intermediate the front and back walls 50 with the internal shoulder produced by offsetting facing the front wall, and windows in the shouldered part of said roof and windows in said shoulder.

3. A hangar comprising a plurality of radiating stalls each with a floor plan of substantially trapezoidal form, said stalls being arranged about a central roofed space, each stall having a roof downwardly offset between its inner and outer ends, the inner ends of the 60 roof sections being lower than the roof section of the central space whereby a substantially annular depression is formed, the inner and outer walls of said depression having windows, said central space being of a size 65 to receive the fuselage of a plane, said stalls

having each a door in its inner wall permitting removal of the fuselage from the stall to said central space.

4. A hangar comprising a plurality of radiating stalls each with a floor plan of substantially trapezoidal form, said stalls being arranged about a central roofed space, each stall having a roof downwardly offset between its inner and outer ends, the inner ends of the roof sections being lower than the roof section of the central space whereby a substantially annular depression is formed, the inner and outer walls of said depression having windows, said central space being of a size to receive the fuselage of a plane, said stalls 70 having each a door in its inner wall permitting removal of the fuselage from the stall to said central space, and means affording access to said central space independently of 75 passage through any of said stalls.
